(57) **CLAIM**

We claim, the ornamental design for a multi-handled tool, as shown and described.

DESCRIPTION

FIG. 1 is a perspective view of the multi-handled tool;
FIG. 2 is a front view of the multi-handled tool;
FIG. 3 is a back view of the multi-handled tool;
FIG. 4 is a right side view of the multi-handled tool;
FIG. 5 is a left side view of the multi-handled tool;
FIG. 6 is an enlarged top view of the multi-handled tool;
and,
FIG. 7 is an enlarged bottom view of the multi-handled tool. The broken lines in the drawings illustrate portions of the multi-handled tool that form no part of the claimed design. The thin lines located on the blade portion of the shovel indicate contours and form no part of the claimed design.
